CLAIM

The ornamental design for a handle for kitchen utensil, as shown and described.

DESCRIPTION

FIG. 1 is a perspective view of a handle for kitchen utensil, the utensil head shown in broken lines is for illustrative purposes only and forms no part of the claimed design; FIG. 2 is a top view of the handle shown in FIG. 1; FIG. 3 is a bottom view of the handle shown in FIGS. 1 and 2;

FIG. 4 is a side view of the handle shown in FIGS. 1-3, both sides being identical;

FIG. 5 is a front end view of the embodiment of the handle shown in FIGS. 1-4; and,

FIG. 6 is a rear end view of the handle shown in FIGS. 1-5.
